United States Patent Office.

EDWARD S. DAWSON, OF SYRACUSE, NEW YORK.

Letters Patent No. 86,822, dated February 9, 1869.

IMPROVED TRACE-BUCKLE.

The Schedule referred to in these Letters Patent and making part of the same.

To all whom it may concern:

Be it known that I, EDWARD S. DAWSON, of Syracuse, in the county of Onondaga, and State of New York, have invented a new and improved Trace-Buckle; and I do hereby declare that the following is a full, clear, and exact description thereof, which will enable those skilled in the art to make and use the same, reference being had to the accompanying drawings, forming part of this specification, in which—

Figure 1 is a front view,

Figure 2 is an edge view, and

Figure 3 is a sectional edge view.

Similar letters of reference indicate like parts.

This invention consists in a buckle formed by securing a wedge-shaped piece to the hames-tug in a permanent manner, and providing, in connection therewith, a buckle-frame, of such construction that said wedge makes a jamming connection with the buckle-frame and tug, when strain is applied, as hereinafter described.

In the accompanying drawings—

E is the tug, and F, the hames-tug.

A is the buckle-frame, having a wide cross-bar, a, and opposite thereto a round cross-bar, b, fig. 3, and having also a fixed projection, or tongue, at c.

The wedge D is pivoted to the hames-tug by means of a rivet or screw, d.

When a strain is brought upon the tug, the wedge D is forced in between the tug and the bar b, until the tug is clamped so firmly between the wedge and wide bar a, as to make a strong and secure connection

between the two parts of the tug, without any liability of damage to the tug.

The buckle-frame A is provided with a tongue, c, fig. 3, which engages with holes in the tug, in the ordinary manner, although the office of this tongue is mainly to do the spacing in taking up or letting out the tugs, and to steady them in position.

For changing the length of the tug, the wedge D is first backed up, and this allows the tongue c to be withdrawn and changed to any desired hole in the tug.

The rivet d can be cast solid with the wedge D, as a part thereof, and sewn into the hames-tug, if preferred, and in this manner the buckle is composed of two pieces, which are cast complete, and require no fitting.

The exposed face of the buckle presents a neat and snug appearance, and by these means I obtain a very simple, cheap, and efficient buckle.

Having thus described my invention,

What I claim as new, and desire to secure by Letters Patent, is—

The buckle-frame A a b c and hames-tug attachment D d, constructed and operating as and for the purpose specified.

The above specification of my invention signed by me, this 28th day of December, 1868.

E. S. DAWSON.
